Primary Examiner — Mary Ann Calabrese*Assistant Examiner* — Harper E Comstock(74) Attorney, Agent, or Firm — Bayramoglu Law Offices LLC(57) CLAIM

The ornamental design for a baby bassinet, as shown and described.

DESCRIPTION

FIG. 1 is a first perspective view of a baby bassinet showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a second perspective view thereof.

The broken lines in the drawings illustrate portions of the baby bassinet that form no part of the claimed design.

1 Claim, 8 Drawing Sheets(56)
